UNITED STATES PATENT OFFICE.

JOHN J. PFISTER, OF BERKELEY, CALIFORNIA.

DESIGN FOR A BABY'S HOOD.

54,119.

Specification for Design.

Patented Nov. 4, 1919.

Application filed April 7, 1919. Serial No. 288,392. Term of patent 14 years.

To all whom it may concern:

Be it known that I, JOHN J. PFISTER, a citizen of the United States, residing in Berkeley, county of Alameda, and State of California, have invented a new, original, and ornamental Design for Babies' Hoods, of which the following is a specification, reference being had to the accompanying drawings, forming part thereof.

Fig. 2 is a perspective view of the same.

I claim:

The ornamental design for a baby's hood, as shown.

JOHN J. PFISTER.
